UNITED STATES PATENT OFFICE

2,644,492

SAFETY LOCK FOR BAND SAW TENSIONING
MECHANISM

Robert L. Crane, Savage, Minn., assignor to Continental Machines, Incorporated, Savage, Minn., a corporation of Minnesota

Application June 21, 1950, Serial No. 169,501

6 Claims. (Cl. 143—27)

1

My invention relates generally to machine tools of the type utilizing a cutting band such as band saws or the like, and more specifically to mechanism in machine tools of this type for maintaining a desired minimum of tension on the cutting band.

In band saws of the type wherein cutting band tension is maintained by shifting one of the pulleys over which the cutting band is trained, and particularly when the pulley is shifted by means of fluid pressure operated mechanism, there is frequently a tendency for the shiftable pulley to move in a direction relieving tension on the band when the machine is at rest. Then when the machine is again put into operation, the cutting band is so loosely engaged by the pulley over which it runs that it fails to track properly thereon and runs off the pulley before sufficient tension is applied thereto. When this occurs, the band is frequently damaged and possible danger to the operator results. The primary object of my invention is, therefore, the provision of means for preventing undue release of tension of the cutting band in machines of this type when the machine is in an inoperative condition.

Another object of my invention is the provision of means for preventing release of tension of the cutting band for an indefinite period of time.

Another object of my invention is the provision of brake mechanism associated with the mounting means for the shiftable pulley and normally set in braking engagement to arrest shifting movements of the shiftable pulley in a band tension releasing direction, and of means responsive to normal operation of the machine for urging the brake toward a brake released position.

Another object of my invention is the provision of brake mechanism as set forth having an extendable and retractable element normally extended to a braking position, and of fluid pressure means for urging said element toward a brake released position during normal operation of the machine.

Still another object of my invention is the provision of means for locking the shiftable pulley mounting against band tension releasing movement, which is simple and inexpensive to produce, which is rugged in construction, and which is efficient in operation and durable in use.

Other highly important objects and advantages of my invention will become apparent from the following detailed specification, appended claims, and attached drawings.

Referring to the drawings, which illustrate the invention, and wherein like characters indicate like parts throughout the several views:

2

Fig. 1 is a view in front elevation of a sawing machine band made in accordance with my invention;

Fig. 2 is an enlarged vertical section taken on the line 2—2 of Fig. 1;

Fig. 3 is a fragmentary detail partly in front elevation and partly in section taken substantially on the line 3—3 of Fig. 2;

Fig. 4 is an enlarged axial section of one of the brake elements of my invention taken substantially on the line 4—4 of Fig. 3; and

Fig. 5 is a diagrammatic view illustrating a fluid pressure system of my invention.

Referring with greater detail to the drawings, a band saw machine is indicated in its entirety by the numeral 1, the fixed frame structure of which comprises a base 2, a generally vertical column 3 and a head 4. The head 4 projects laterally outwardly from the upper end of the column 3 overlying a laterally projected portion of the base 2 to define therebetween a throat or working space in which is disposed a work-supporting table 5 mounted on the extended end portion of the base 2. A drive wheel 6 is mounted on the base 2 below the table 5, and an idler wheel or pulley 7 is mounted for rotation in the head 4 in tandem relationship to the drive wheel 6. An endless cutting band 8, in the nature of a band saw or the like, is trained over the wheels 6 and 7 and through a slot 9 in the work table 5, and guided by guide rollers 10 of a saw guide 11 secured to the head 4 by means of a supporting post 12. The drive wheel 6 is mounted fast on a shaft 13, which is driven from a drive motor 14, by means of V-belts 15 and 16, indicated by dotted lines in Figs. 1 and 5, a conventional variable speed pulley 17 and suitable transmission mechanism, not shown, but contained within the base 2. The variable speed pulley 17 is journaled to a mounting bracket 18 pivotally secured to the base 2, as indicated at 19. The variable speed pulley 17, the belts 15 and 16, and transmission mechanism, not shown, form no pertinent part of the instant invention, and it is thought that detailed showing and description thereof is therefore unnecessary.

The idler pulley 7 is mounted fast on the outer end of a shaft 20, which is journaled in floating bearing bracket 21 by means of anti-friction bearings 22. The bearing bracket 21 is pivotally mounted on a shaft 24 extending transversely of a mounting member 25 which is mounted for vertical sliding movement on a fixed plate 26 rigidly secured to a wall section 27 of the head 4 by nut-equipped bolts or the like 28. The bearing bracket 21 is provided with an upstanding lug 29,

which forms the base of support for one end of a compression spring 30 interposed therebetween and the upper end portion of the mounting member 25, whereby to bias the bearing bracket 21 in one direction of pivotal movement about the axis of the shaft 24. A depending ear 31 integrally formed with the bearing bracket 21 is adapted to have abutting engagement with one end of a push rod 32 axially slidable in a laterally extended boss 33 integrally formed with the mounting member 25 at its lower end portion. The push rod 32 is adapted to be moved by an adjustment knob or handle wheel 34 rigidly mounted on a vertical shaft 35 journaled in the bottom portion of the head 4. The upper end of the shaft 35 is cross-sectionally polygonal, as indicated at 36 and has telescoping engagement with the lower end of a sleeve 37, the upper end of which telescopes over the lower end 38 of a screw threaded shaft 39. The shaft 39 has screw threaded engagement with a threaded portion of a bracket 40 integrally formed with the boss 33, and engages one side of a block-like lever 41 pivotally mounted on the bracket 40. A portion of the lever 41 engages the projecting end of the push rod 32 and is adapted to move the push rod upon rotation of the knob 34 in one direction against bias of the compression spring 30. Rotation of the knob 34 in the opposite direction will cause the idler wheel 7 to be tilted in the opposite direction. It should be noted that when the cutting band 8 is mounted on the wheels 6 and 7, tension of the cutting band 8 will be added to the bias of the spring 30 to cause the depending ear 31 to bear against the adjacent end of the push rod 32. This load is transferred through the lever 41 to the screw 39 and the bracket portion 40 in all positions of the mounting member 25 with respect to the plate 26. By reference to Fig. 2, it will be seen that the telescopic sliding relationship between the lower end 38 of the screw 39 and the sleeve 37 permits free vertical movement of the screw 39 and associated parts with respect to the knob 34.

For the purpose of raising and lowering the idler wheel 7 and mounting member 25 therefor with respect to the drive wheel 6 to make possible the application of the cutting band 8 to the wheels 6 and 7 and apply proper tension to the cutting band 8, I provide a fluid pressure motor in the nature of a fluid pressure actuator cylinder 42 and a cooperating piston 43. The piston 43 depends from the lower end of the mounting plate 26 and is securely held by means of screws or the like 44. A plunger rod 45 has its lower end rigidly secured to the piston 43, and extends upwardly through the upper end of the cylinder 42, having its upper end mounted fast on the lower end portion 46 of the mounting member 25.

Fluid under pressure is supplied selectively to opposite ends of the cylinder 42 from a supply tank 47 by a pump 48 driven from the motor 14 through the medium of a V-belt 49 running over suitable pulleys on the motor and pump. The pump 48 is interposed in a fluid pressure conduit 50 which extends to a check valve 51 in a valve block 52. A passage 53 in the valve block 52 extends from the check valve 51 to a valve chamber 54 in which is mounted a directional valve element 55. A pair of conduits 56 and 57 extend from the valve chamber 54 to the lower and upper ends respectively of the cylinder 42. As shown in Fig. 5, the valve element 55 is formed to provide circumferentially spaced axially extending faces or sides 58, 59, and 60, which cooperate with the

circular wall of the chamber to define respective circumferentially spaced valve compartments 58', 59', and 60'. The valve element 55 is further provided adjacent one end with a transverse passage 61 extending from the face 58 to the side of the element 55 between the faces 59 and 60. A second passage 62 extends axially inwardly from the opposite end of the valve element 55 terminating short of the transverse passage 61 and has communication with a pair of passages 63 which extend radially inwardly one each from one of the faces 59 and 60. A passage 64 in the valve block 52 communicates with the passage 62 and has connection with a fluid return conduit 65 leading therefrom to the supply tank 47. As shown, a pressure relief valve 66 has connection with the fluid pressure conduit 50 as indicated at 67, and with the return conduit 65 as at 68. Manipulation of the valve element 55 by means of its handle 55' (see Fig. 1) to the position thereof shown in Fig. 5 permits fluid to be forced under pressure from the supply tank 47 through the pressure conduit 50, the passage 53 leading therefrom to the chamber 58', the passage 61 in the valve element 55, and the conduit 57 to the lower end portion of the cylinder 42, whereby to raise the piston 43 and the mounting member 25, thus applying tensioning pressure to the cutting band 8.

Use of cutting bands of various widths of the type exemplified generally requires that blades of different widths are maintained at different degrees of tension. For the purpose of applying proper tensioning pressure to bands of different widths, I provide an adjusting pressure regulator valve 69 in the valve block 52. As shown in Fig. 5, one side of the pressure regulator valve 69 communicates with the passage 53 in the valve block 52 through a conduit 70 and a passage 71. The opposite side of the valve 69 communicates with the fluid return conduit 65 by a passage 72 in the valve block 52 extending to the passage 64 therein. A conventional pressure gauge 73 is shown as being connected to the conduit 70 for indicating the exact pressure applied to the piston 43. Inasmuch as the pump 48 operates continually during operation of the machine and delivers a constant supply of fluid, the greater part of the fluid supplied to the valve block 52 is by-passed through the pressure regulator valve 69 and returns to the supply tank 47. During upward movements of the piston 43, fluid in the upper portion of the cylinder 42 will be moved through the conduit 56 into the chamber 58' from whence it will flow through the passage 63 extending inwardly from the face 59 and passage 62 of the valve element 55 into passage 64 and return conduit 65 to the supply tank 47. Movement of the valve element 55 in a clockwise direction with respect to Fig. 5, sufficient to effect communication through the passage 61 with the conduit 56, will cause fluid under pressure to be delivered through the conduit 56 to the upper portion of the cylinder 42 to cause downward movement of the piston 43 and subsequent loosening of tension of the cutting band 8.

Inasmuch as the pump 48 is dependent for its operation on the motor 14, shutting down of the motor 14 will shut off band tensioning pressure of fluid to the lower end portion of the cylinder 42. It should be noted however that the check valve 51 prevents immediate return of fluid backwardly through the pump 48 from the lower end of the cylinder 42. However, when the machine has been idle for an appreciable length of time,

fluid will tend to seep slowly between the wall of the cylinder 42 and the piston 43 contained therein to the upper part of the cylinder thereby permitting downward movement of the pulley mounting member 25 and consequent loosening of the tension on the cutting band 8. When the machine has been idle from one working day to the next, this downward movement of the shiftable pulley mounting member 25 will frequently be sufficient to cause loosening in the cutting band to a point where, when the machine is again put into operation, the band 8 will run off of the pulleys 6 and 7 and become tangled in the machine before the operator can render the same inoperative. To prevent this movement of the shiftable pulley 1 and the mounting member 25 therefor in a band tension releasing direction, I provide novel brake means including cooperating brake elements 74 and 75, the former of which comprises a toothed rack 16 extending in the direction of movement of the pulley mounting member 25 and secured thereto by bolts or the like 77, and the latter of which comprises an extendable and retractable piston plunger 79 slidably mounted in and projecting outwardly from a bearing 79' of a fluid pressure cylinder 78 rigidly secured to the fixed wall section 27 of the machine. The plunger rod 79 is rigidly secured at its inner end to a piston 80 slidably mounted in the cylinder 78 and is disposed at an angle with respect to the rack 16 whereby the outer free end of the plunger rod 79 will engage one of the teeth of the rack 16 when the plunger rod 79 is in an extended position. The plunger rod 79 and piston 80 are normally urged toward braking engagement of the plunger 79 with the rack 16, to arrest downward movement of the shiftable pulley mounting member 25, by a coil compression spring 81 one end of which thrusts against the piston 80 and the other end of which engages the inner end of an adjustable abutment screw 82 which is threaded into an end wall 83 of the cylinder 78. A lock nut 84, screw threaded on the abutment screw 82, when tightened against the end wall 83 prevents accidental movement of the abutment screw 82. I further provide a stop screw 85 extending axially of the abutment screw 82 and operative to limit movement of the piston 80 and plunger rod 79 in a direction against bias of the spring 81.

The fluid motor piston 80 divides the cylinder 78 into chambers 86 and 87, the former of which is a pressure chamber communicating with the pump 48 through a fluid conduit 88 one end of which is coupled to a passage 89 leading to the chamber 86 through the side wall of the cylinder 78, and the other end of which is connected to a conduit 70. The chamber 87, in which is contained the spring 81, communicates with a conduit 90 through a passage 91 in the side wall of the cylinder 78, the conduit 90 being connected to the return conduit 65. The piston 80 is responsive to fluid pressure in the chamber 86 to move the piston plunger 79 in a direction away from engagement with the rack 16 to permit shifting movement of the shiftable pulley mounting member 25 in opposite directions. Fluid which may escape from the chamber 86 to the chamber 87 around the piston 80 is carried back to the supply tank 47 through conduits 90 and 65. It should be noted that the connection of the conduit 88 to the conduit 70 permits fluid under pressure to be introduced to the chamber 86 whenever the fluid pump 48 is in operation and irrespective of the position of the directional

valve element 55. When the motor 14 has been rendered inoperative and sufficient leakage of fluid has occurred between the side wall of the cylinder 42 and the piston 43 therein to permit downward movement of the shiftable pulley mounting member 25, the reduction of fluid pressure in the system permits the spring 81 to move the piston 80 and plunger 79 outwardly into engagement of the outer end of the plunger rod 79 with one of the teeth of the rack 16 to arrest further downward movement of the shiftable pulley 1 and its mounting member 25. The pressure of the spring 81 may be adjusted by the adjusting screw 82 so that braking engagement of the plunger rod 79 with the rack 16 takes place before the shiftable pulley 1 is dropped to a point where the cutting band 8 has become unduly loosened. As above indicated, this braking action caused by pressure of the spring 81 may be held indefinitely. Then, when the machine is again put into operation, fluid pressure set up in the system by the pump 48 simultaneously urges the piston 43 in an upward direction and the piston 80 in a brake releasing direction whereby the shiftable pulley is again free for shifting movements. Obviously, the pressure of the spring 81 is adjusted to exert slightly less pressure against the piston 80 in a brake setting direction than the minimum band tensioning pressure utilized under normal operating conditions of the machine, so that pressure of the spring 81 will be overcome immediately after the pump 48 has been put into operation and regardless of the band tensioning pressure used within a predetermined pressure range.

My invention has been thoroughly tested and found to be completely satisfactory for the accomplishment of the above objects; and while I have shown and described a commercial embodiment of my novel structure, it will be understood that the same is capable of modification without departure from the spirit and scope of the invention as defined in the claims.

What I claim is:

1. In a machine of the class described, a fixed supporting structure, a plurality of pulleys, a cutting band trained over said pulleys, means mounting one of said pulleys for shifting movements toward and from the other pulley structure to effect tightening and loosening of the band, a normally set brake associated with the shiftable pulley mounting for arresting band-loosening movements of the shiftable pulley, said brake comprising cooperating brake elements, structure mounting one of the brake elements on the fixed supporting structure and the other thereof on the shiftable pulley mounting means and guiding one thereof for movements toward and away from the other thereof, yielding means urging said movable brake element toward its cooperating brake element to set the brake, and releasable pressure means associated with the brake and with said means mounting the shiftable pulley for urging the shiftable pulley mounting in a direction to tighten said band and for simultaneously urging said movable brake element in a brake-releasing direction away from its cooperating brake element against bias of said yielding means, said yielding means being responsive to release of said releasable pressure means to move said movable brake element toward brake setting engagement with its cooperating brake element.

2. In a machine of the class described, a fixed supporting structure, a plurality of pulleys, a

cutting band trained over said pulleys, means mounting one of said pulleys for shifting movements toward and from the other pulley structure to effect tightening and loosening of the band, a normally set brake associated with the shiftable pulley mounting for arresting band-loosening movements of the shiftable pulley, said brake comprising cooperating brake elements, structure mounting one of the brake elements on the fixed supporting structure and the other thereof on the shiftable pulley mounting means and guiding one thereof for movements toward and away from the other thereof, yielding means urging said movable brake element toward its cooperating brake element to set the brake, releasable power operated mechanism associated with the shiftable pulley mounting for urging the shiftable pulley mounting in a band-tightening direction, releasable power operated mechanism associated with said brake for releasing the brake against bias of said yielding means, and manually-operated control mechanism for said first mentioned releasable power operated mechanism.

3. In a machine of the class described, a fixed supporting structure, a plurality of pulleys, a cutting band trained over said pulleys, means mounting one of said pulleys for shifting movements toward and from the other pulley structure to effect tightening and loosening of the band, a normally set brake associated with the shiftable pulley mounting for arresting band loosening movements of the shiftable pulley, said brake comprising cooperating brake elements, structure mounting one of the brake elements on the fixed supporting structure and the other thereof on the shiftable pulley mounting means and guiding one thereof for movements toward and away from the other thereof, yielding means urging said movable brake element toward its cooperating brake element to set the brake, and a fluid pressure system including a pump, a fluid pressure motor located adjacent the shiftable pulley mounting for urging said shiftable pulley mounting in a band-tightening direction, and a second fluid pressure motor associated with said movable brake element and operative to urge the movable brake element in a brake-releasing direction against bias of said yielding means, said yielding means moving said movable element toward brake setting engagement with its cooperating brake element responsive to release of pressure when the pump is rendered inoperative.

4. In a machine of the class described, a fixed supporting structure, a plurality of pulleys, a cutting band trained over said pulleys, means mounting one of said pulleys for shifting movements toward and from the other pulley structure to effect tightening and loosening of the band, a normally set brake associated with the shiftable pulley mounted for arresting band-loosening movements of the shiftable pulley, said brake comprising a rack element and a cooperating pawl element, structure mounting one of said elements on the fixed supporting structure and the other thereof on the shiftable pulley mounting means and guiding said pawl element for movements toward and from the rack element to set and release the shiftable pulley mounting, yielding means biasing the pawl element toward the rack element, and releasable pressure means associated with the brake and

with said means mounting the shiftable pulley for urging the shiftable pulley in a direction to tighten said band and for simultaneously urging said pawl element in a direction away from said rack element against bias of said yielding means, said yielding means being responsive to release of said releasable pressure means to move said pawl element toward engagement with said rack element.

5. In a machine of the class described, a fixed supporting structure, a plurality of pulleys, a cutting band trained over said pulleys, means mounting one of said pulleys for shifting movements toward and from the other pulley structure to effect tightening and loosening of the band, a normally set brake associated with the shiftable pulley mounted for arresting band-loosening movements of the shiftable pulley, said brake comprising a rack element and a cooperating pawl element, structure mounting one of said elements on the fixed supporting structure and the other thereof on the shiftable pulley mounting means and guiding said pawl element for movements toward and from the rack element to set and release the shiftable pulley mounting, yielding means biasing the pawl element toward the rack element, releasable power operated mechanism associated with the shiftable pulley mounting for urging the shiftable pulley mounting in a band-tightening direction, releasable power-operated mechanism associated with said pawl element for moving the pawl element away from said rack element against the action of said yielding means, and manually operated control mechanism for said first mentioned releasable power operated mechanism.

6. In a machine of the class described, a fixed supporting structure, a plurality of pulleys, a cutting band trained over said pulleys, means mounting one of said pulleys for shifting movements toward and from the other pulley structure to effect tightening and loosening of the band, a normally set brake associated with the shiftable pulley mounting for arresting band-loosening movements of the shiftable pulley, said brake comprising a rack mounted for common movements with the shiftable pulley mounting and a pawl, means mounting said pawl on the fixed supporting structure and guiding said pawl for movements toward and from the rack to set and release the shiftable pulley mounting, a spring biasing the pawl toward the rack, and a fluid pressure system including a pump, a fluid pressure motor located adjacent the shiftable pulley mounting for urging said shiftable pulley mounting in a band-tightening direction, a second fluid pressure motor for moving the pawl in a direction away from said rack against bias of said spring, and a common control valve for said motors, said spring moving said pawl toward brake-setting engagement with the rack responsive to release of pressure when the pump is rendered inoperative.
